UNITED STATES PATENT OFFICE.

PAUL GRÜNEWALD, OF DUISBURG, GERMANY.

MARINE BOILER.

SPECIFICATION forming part of Letters Patent No. 740,270, dated September 29, 1903.

Application filed August 21, 1902. Serial No. 120,460. (No model.)

To all whom it may concern:

Be it known that I, PAUL GRÜNEWALD, a subject of the Emperor of Germany, and a resident of Duisburg, Germany, have invented a new and Improved Marine Boiler, of which the following is a full, clear, and exact description.

The object of the invention is to provide a new and improved boiler, more especially designed as a marine boiler and arranged to insure quick heating of the water and generation of steam to a high pressure with safety and without requiring undue increase in the thickness of the boiler material.

15 The invention consists of novel features and parts and combinations of the same, as will be more fully described hereinafter and then pointed out in the claims.

A practical embodiment of the invention 20 is represented in the accompanying drawings, forming a part of this specification, in which similar characters of reference indicate corresponding parts in all the views.

Figure 1 is a front elevation of the improvement, parts being in section, on the line 1 1 of Fig. 4. Fig. 2 is a sectional side elevation of the same on the line 2 2 of Fig. 1. Fig. 3 is a sectional front elevation of the same on the line 3 3 of Fig. 2, and Fig. 4 is a sectional plan view of part of the improvement 30 on the line 4 4 of Fig. 3.

The improved boiler is provided with transversely-extending front and rear water-chambers A and B, spaced a suitable distance 35 apart and connected with each other at their inner or opposite faces by large water-tubes C, preferably four in number, as plainly illustrated in the drawings. The front water-chamber A is set on the front wall D of a fire-box E, having the usual charging-doors E¹, grate E², ash-pit E³, and doors E⁴, leading to the said ash-pit. The rear ends of the grate E² terminate or extend to a fire-clay wall E⁵ at the inner face of the lower end of the rear 45 water-chamber B. (See Fig. 2.)

Through each of the large water-tubes C extend smoke-return flues F, having their rear ends extending through the outer face of the rear water-chamber B, and the said 50 smoke-return flues F have their front ends extending through a removable section A', forming part of the front face of the front

water-chamber A. Short smoke-flues G extend longitudinally through the front water-chamber A and its front and rear faces, and 55 similar short smoke-flues G' extend longitudinally through the rear water-chamber B and its front and rear faces, as will be readily understood by reference to Fig. 2, it being, however, expressly understood that the said 60 short smoke-flues G and G' are located outside the large water-tubes C.

A feed-water pipe H is connected at or near its middle with a suitable supply, and the said feed-water pipe extends transversely in the 65 lower portion of the front water-chamber A, and the ends of the said feed-water pipe H open into feed-water chambers I, formed at the sides of the front water-chamber A, as plainly illustrated in the drawings. The feed- 70 water chambers I are connected by pipes J with stand-pipes K, connecting a mud-drum L with a steam-drum N, the said pipes J on each side of the boiler being located one above the other, so as to form side walls for 75 the boiler.

The mud-drum L is arranged in the rear of the lower end of the rear water-chamber B and is connected with the same by branch pipes L', so that the feed-water can circulate 80 from the chambers I through the pipes J into the stand-pipes K to the mud-drum L and through the branch pipes L' into the rear water-chamber B, from which the water can pass through the large water-tubes C into the 85 front water-chamber A.

The upper ends of the stand-pipes K support the steam-drum N, previously mentioned, and pipes O of small diameter connect the top of the mud-drum L with the bottom of the 90 steam-drum N between the stand-pipes K, so that the said pipes O form the rear wall of the boiler.

The upper end of the front water-chamber A is connected by pipes P with the steam-drum N, and the said pipes P are arranged one alongside the other to form the top wall of the boiler.

Now by the arrangement described water 100 passing into the front water-chamber A, as previously mentioned, can readily pass through the pipes P into the steam-drum N, and the water can circulate down from the steam-drum by the stand-pipes K into the

mud-drum L, and the water can rise from the latter through the pipes O back into the steam-drum N. Thus by the arrangement described a very free circulation of the water is obtained, and the steam can readily pass and accumulate in the steam-drum N. It will further be seen that by the arrangement described the feed-water in passing through the feed-water pipe H, chambers I, and pipes J receives a preliminary heating, and any scale forming in the water is readily carried to the mud-drum L to accumulate therein and to be removed therefrom from time to time through suitable manholes in the ends of the drum.

In order to obtain convenient access to the interior of the front water-chamber A and water-tubes C, I provide the section A' with a manhole A², the said section A' when removed from the front face of the water-chamber A giving access to the tubes C to permit removal and renewal of the same whenever necessary.

The forward ends C' of the large water-tubes C are somewhat enlarged and are riveted to flanges A³ on the rear face of the front water-chamber A to allow convenient withdrawal of a tube C whenever it is necessary to renew the same when worn out. The rear ends of the tubes C are similarly riveted to flanges B' on the inner face of the rear water-chamber B. Packing-rings may be interposed between the flanges A³ and B' and the ends of the tubes C, as indicated in Fig. 2.

On the front face of the water-chamber A is secured the usual smoke-box Q for connection with the chimney or stack, and into the said smoke-box Q open the flues F and G. The pipes O, forming the rear wall of the boiler, are spaced a distance from the outer face of the water-chamber B, so as to form with the latter a space R for the passage of the smoke, which may readily enter the rear ends of the smoke-return flues F.

It is understood that when the boiler is in operation the heat and gases arising from the fuel burning in the fire-box E pass up between the large water-tubes C, and part of the smoke and gases passes through the flues G' to the chamber R, and another portion passes under the pipes P to the said chamber, and then the smoke and gases pass forward to the flues F and into the smoke-box Q, and a portion of the gases may also pass through the short smoke-flues G to the said smoke-box.

It is understood that the top of the rear water-chamber B coincides with the tops of the rear ends of the tubes C, while the front water-chamber A is extended above the tubes C to accommodate the pipes P. Now by this arrangement no dead-water space is formed in the rear water-chamber B, and consequently the water in this chamber flows readily forward in the somewhat upwardly-inclined tubes C, which deliver water to the front water-chamber A.

The bottom of the chamber R is preferably closed by doors S under the control of the operator to permit of conveniently removing soot and the like accumulating in the said chamber. The side connecting-pipes J are preferably covered on the outside with a fire-clay wall T, and the pipes P are similarly covered by a top T', and the pipes O are backed by a like fire-clay wall T², so as to prevent the escape of smoke and gases from the boiler.

Having thus described my invention, I claim as new and desire to secure by Letters Patent—

1. A boiler comprising front and rear transversely-extending water-chambers, large longitudinal water-tubes connecting the chambers with each other at their inner adjacent faces, smoke-return flues extending longitudinally through the said water-tubes and through the outer faces of the water-chambers, and short smoke-flues extending longitudinally through each of the water-chambers, as set forth.

2. A boiler, comprising front and rear transversely-extending water-chambers, large longitudinal water-tubes connecting the said chambers with each other, smoke-return flues extending longitudinally through the water-tubes and through the outer faces of the water-chambers, a transverse mud-drum in the rear of the rear water-chamber and connected with the lower end thereof, a transversely-extending steam-drum in the upper part of the boiler, stand-pipes supporting the steam-drum and connecting it with the mud-drum, and pipes connecting the mud and steam drums and forming the rear wall of the boiler, as set forth.

3. A boiler comprising front and rear transversely-extending water-chambers, large longitudinal water-tubes connecting the chambers with each other at their inner adjacent faces, smoke-return flues extending longitudinally through the said water-tubes and through the outer faces of the water-chambers, a transverse mud-drum in the rear of the rear water-chamber and connected with the lower end of the said rear water-chamber, feed-water chambers at the sides of the front water-chamber and connected with the feed-water supply, stand-pipes rising from the said mud-drum, and longitudinal side connecting-pipes connecting the feed-water chambers with the said stand-pipes, as set forth.

4. A boiler comprising front and rear transversely-extending water-chambers, large longitudinal water-tubes connecting the chambers with each other at their inner adjacent faces, smoke-return flues extending longitudinally through the said water-tubes and through the outer faces of the water-chambers, a transverse mud-drum in the rear of the rear water-chamber and connected with the lower end of the said rear water-chamber, feed-water chambers at the sides of the front water-chamber and connected with the feed-water supply, stand-pipes rising from the said

mud - drum, longitudinal side connecting-pipes connecting the feed - water chambers with the said stand-pipes, a steam-drum on the said stand-pipes, in communication there-
5 with, and rear connecting-pipes connecting the steam-drum with the mud-drum between the stand-pipes, as set forth.

5. A boiler comprising front and rear trans-
versely-extending water-chambers, large lon-
10 gitudinal water-tubes connecting the cham-
bers with each other at their inner adjacent
faces, smoke-return flues extending longitudinally through the said water - tubes and
through the outer faces of the water-cham-
15 bers, a transverse mud-drum in the rear of
the rear water-chamber and connected with
the lower end of the said rear water-chamber,
feed-water chambers at the sides of the front
water-chamber and connected with the feed-
20 water supply, stand-pipes rising from the said
mud - drum, longitudinal side connecting-
pipes connecting the feed - water chambers
with the said stand-pipes, a steam-drum on
the said stand-pipes, in communication there-
25 with, and rear connecting-pipes connecting
the steam-drum with the mud-drum between
the stand-pipes, the said rear connecting-
pipes being of small diameter and arranged
one alongside the other, to form a rear wall
30 for the boiler, as set forth.

6. A boiler comprising front and rear wa-
ter-chambers, longitudinal water-tubes of
large diameter connecting the chambers with
each other at their inner adjacent faces,
35 smoke-return flues extending longitudinally
through the water-tubes and the outer faces
of the water-chambers, a transverse mud-
drum formed in the rear of the rear water-
chamber and connected with the lower end
40 thereof, feed-water chambers at the sides of
the front water-chamber and connected with
the feed-water supply, stand-pipes rising from
the mud-drum, and longitudinal side con-
necting-pipes connecting the feed-water cham-
45 bers with the said stand-pipes, the said side
connecting-pipes being arranged one above
the other and in close proximity to each other,
to form the side walls of the boiler, as set
forth.

50. 7. A boiler comprising front and rear wa-
ter-chambers, longitudinal water-tubes of
large diameter connecting the chambers with
each other at their inner adjacent faces,
smoke-return flues extending longitudinally
55 through the water-tubes and the outer faces
of the water-chambers, a transverse mud-
drum formed in the rear of the rear water-
chamber and connected with the lower end
thereof, feed-water chambers at the sides of
60 the front water-chamber and connected with
the feed-water supply, stand-pipes rising from
the mud-drum, longitudinal side connecting-
pipes connecting the feed - water chambers
with the said stand-pipes, the said side con-
65 necting-pipes being arranged one above the
other and in close proximity to each other,
to form the side walls of the boiler, and a

feed-water pipe extending transversely in the
front water-chamber at the lower end there-
of and opening into the lower ends of the said
feed-water chambers, as set forth.

8. A boiler comprising front and rear wa-
ter-chambers, longitudinal water-tubes of
large diameter connecting the chambers with
each other at their inner adjacent faces, 75
smoke-return flues extending longitudinally
through the water-tubes and the outer faces
of the water-chambers, a transverse mud-
drum formed in the rear of the rear water-
chamber and connected with the lower end 80
thereof, feed-water chambers at the sides of
the front water-chamber and connected with
the feed-water supply, stand-pipes rising
from the mud-drum, longitudinal side con-
necting - pipes connecting the feed - water 85
chambers with the said stand-pipes, the said
side connecting - pipes being arranged one
above the other and in close proximity to
each other, to form the side walls of the
boiler, a steam-drum on the said stand-pipes, 90
and longitudinal top connecting-pipes, for
connecting the upper end of the front water-
chamber with the said steam-drum, as set
forth.

9. A boiler comprising front and rear trans-
versely-extending water-chambers, large lon-
gitudinal water-tubes connecting the cham-
bers with each other at their inner adjacent
faces, smoke-return flues extending longi-
100 tudinally through the water-tubes and the
outer faces of the water-chambers, a mud-
drum in the rear of the rear water-chamber
and connected with the lower end of the said
rear water-chamber, a steam-drum, stand-
105 pipes supporting the steam-drum and con-
necting it with the mud - drum, a series of
pipes connecting the steam and mud drums,
and top connecting water-pipes connecting
the upper end of the front water-chamber
110 with the said steam-drum, the said connect-
ing water-pipes forming the top and rear wall
of the boiler, as set forth.

10. A boiler comprising front and rear
transversely-extending water-chambers, large
longitudinal water - tubes connecting the 115
chambers with each other at their inner ad-
jacent faces, smoke-return flues extending
longitudinally through the water-tubes and
the outer faces of the water-chambers, a mud-
drum in the rear of the rear water-chamber and
120 connected with the lower end of the said rear
water-chamber, a steam-drum, stand - pipes
connecting the mud-drum with the steam-
drum, top connecting water-pipes connecting
the upper end of the front water-chamber 125
with the said steam-drum, the said connect-
ing water-pipes forming the top of the boiler,
above the uppermost water-tubes, and small
pipes forming the rear wall of the boiler and
connecting the steam - drum with the mud- 130
drum, the said rear wall being spaced from
the outer face of the rear water-chamber, as
set forth.

11. A boiler, comprising front and rear wa-

ter-chambers, the outer wall of the front chamber having a removable section, longitudinal water-tubes connecting the chambers with each other, the front ends of the water-tubes being secured to the inner wall of the front water-chamber opposite the removable section thereof, and smoke-return flues extending longitudinally through each of the water-tubes, and through the outer wall of the rear water-chamber, the front ends of the smoke-flues of all the water-tubes extending through the removable section of the outer wall of the front water-chamber, as set forth.

12. A boiler comprising front and rear water-chambers, of which the outer face of the front water-chamber has a removable section, longitudinal water-tubes connecting the

chambers with each other at their inner faces, the front ends of the water-tubes being enlarged and located opposite the said removable section, smoke-return flues extending longitudinally through the said water-tubes, through the outer face of the rear water-chamber and through the said removable section of the outer face of the front water-chamber, and a manhole in the said section, as set forth.

In testimony whereof I have signed my name to this specification in the presence of two subscribing witnesses.

PAUL GRÜNEWALD.
